UNITED STATES PATENT OFFICE

115,379

DESIGN FOR A COFFEE ROASTER OR THE LIKE

Donald W. Adams and Richard L. Schuhmann,
Louisville, Ky.

Application April 24, 1939, Serial No. 84,519

Term of patent 14 years

To all whom it may concern:

Be it known that we, Donald W. Adams and Richard L. Schuhmann, citizens of the United States, residing at Louisville, in the county of Jefferson and State of Kentucky, have invented a new, original, and ornamental design for Coffee Roaster or the like, of which the following is a specification, reference being had to the accompanying drawings, forming a part thereof.

In the drawings:

Fig. 1 is a perspective view looking toward the rear and one side of a coffee roaster or the like embodying our design.

Fig. 2 is a perspective view looking toward the front and the opposite side of the coffee roaster or the like shown in Fig. 1.

While the apparatus shown in the drawings is primarily intended for roasting coffee, we wish it understood that the same may be used for roasting any other material adapted for roasting therein.

We claim:

The ornamental design for a coffee roaster or the like, substantially as shown and described.

DONALD W. ADAMS.
RICHARD L. SCHUHmann.
